[57] CLAIM

The ornamental design for a push-up detection device, as shown and described.

DESCRIPTION

FIG. 1 is an environmental left side elevational view in

reduced scale, of a push-up detection device showing my new design;

FIG. 2 is a top plan view thereof;

FIG. 3 is a front elevational view thereof;

FIG. 4 is a left side elevational view thereof;

FIG. 5 is a right side elevational view thereof;

FIG. 6 is a bottom plan view thereof;
FIG. 7 is a top plan view of a second embodiment thereof;
FIG. 8 is a front elevational view of the embodiment of FIG. 6;

FIG. 9 is a left side elevational view of the embodiment of FIG. 6;

FIG. 10 is a right side elevational view of the embodiment of FIG. 6;

FIG. 11 is a bottom plan view of the embodiment of FIG. 6;

FIG. 12 is a top plan view of a third embodiment thereof;

FIG. 13 is a front elevational view of the embodiment of FIG. 12;

FIG. 14 is a left side elevational view of the embodiment of FIG. 12;

FIG. 15 is a right side elevational view of the embodiment of FIG. 12; and,

FIG. 16 is a bottom plan view of the embodiment of FIG. 12.

The broken line showing of a user of the present push-up detection device in FIG. 1 is for illustrative purposes only and forms no part of the claimed design. The rear elevations of the embodiments of FIGS. 1, 6, and 12 are mirror images respectively of the front elevational views of FIGS. 3, 8, and 13.
